Inventor,
By Atty. Earle Seymour

UNITED STATES PATENT OFFICE.

JOHN GARDNER, OF NEW HAVEN, CONNECTICUT, ASSIGNOR TO THE
WINCHESTER REPEATING ARMS COMPANY, OF SAME PLACE.

PRIMER.

SPECIFICATION forming part of Letters Patent No. 572,888, dated December 8, 1896.

Application filed December 9, 1895. Serial No. 571,482. (No model.)

To all whom it may concern:

Be it known that I, JOHN GARDNER, of New Haven, in the county of New Haven and State of Connecticut, have invented a new 5 Improvement in Primers for Cartridge-Shells; and I do hereby declare the following, when taken in connection with the accompanying drawings and the letters of reference marked thereon, to be a full, clear, and exact description of the same, and which said drawings constitute part of this specification, and represent, in—

Figure 1, a detached enlarged view, in central longitudinal section, of a primer constructed in accordance with my invention, showing its body before the contraction thereof to form a retaining-neck; Fig. 2, a similar view showing the primer after the contraction of its body to form the retaining-neck; 20 Fig. 3, a view of the primer in transverse section on the line *a b* of Fig. 3; Fig. 4, a detached perspective view of the anvil; Fig. 5, a view in side elevation of a paper shot-shell containing one of my improved primers, a 25 portion of the head of the shell broken away to show the primer.

My invention relates to an improvement in that class of primers or percussion-caps which are provided with a sheet-metal anvil, the 30 object being to produce a simple and inexpensive primer constructed with particular reference to the invariable explosion of the fulminate, to securing the anvil in the primer-body so firmly that it cannot be forced out of the same by the explosion of the fulminate, and to the free passage of the fire resulting 35 from the explosion of the fulminate out of the primer into the powder in the form of a single tongue of flame.

With these ends in view my invention consists in a primer having certain details of construction, as will be hereinafter described, and 40 pointed out in the claim.

In carrying out my invention I form a 45 primer-body or shell *A* of heavy sheet metal, which, as shown, is upset to form an outwardly-projecting annular bearing-flange *A'* at its outer end. Within the primer-body *A*, I locate in longitudinal arrangement a flat 50 wrought-metal anvil *B*, having corresponding bearing edges *B' B'*, but differentiated ends,

its outer end being pointed to form a high percussion-surface *B²*, and its inner end being indented to form a clearance-space *B³*, which quickens the union of the fire produced 55 by the explosion of the fulminate and passing inward through the passages *B⁴ B⁴*, formed on the opposite sides of the anvil. By constructing the anvil with corresponding bearing edges, but differentiated ends, I greatly facilitate 60 the right assemblage of the anvils with the primer-bodies, inasmuch as the anvils will not enter the bodies sidewise, but only endwise, and the ends of the anvils being so well distinguished from each other 65 there is no difficulty in presenting the right end of the anvil to the open end of the primer-body. The fulminate *C*, which is located within the closed end of the primer-body, is by preference hardened or caked under pressure, so as to retain its place without the use 70 of any covering. The pointed percussion-surface *B²* of the anvil is pressed slightly into the center of the caked fulminate, as shown in Figs. 2 and 3 of the drawings. After the 75 anvil has been introduced into the primer-body it is firmly secured therein by the reduction of the open inner end of the body to form the cylindrical, longitudinally-projecting, thickened, and condensed, and therefore 80 reinforced, retaining-neck *A²*, as shown in Fig. 2, the said neck being considerably smaller in diameter than the width of the anvil.

The reduction of the open inner end of the 85 primer-body to form the retaining-neck is by preference done gradually by a series of diminishing reducing-dies. The described reduction of the primer-body to form the retaining-neck enables me to employ heavier 90 sheet metal in the production of the primer than I could use in case I depended upon turning the edge of the open end of the primer inward upon itself for securing the anvil in place, the method last mentioned weakening 95 the metal, reducing it in thickness, and affording less security to the anvil.

By contracting the open end of the primer-body to form a retaining-neck as described I not only condense and thicken the metal, 100 as shown in Fig. 2, but am enabled to secure the anvil so firmly in place that it cannot be

forced out by the explosion of the fulminate. This is a very important feature of my improved primer, because if the force of explosion on the fulminate could blow the anvil out of the primer the same would be carried out of the shell and perhaps be as fatal in its effect as a ball, so that the firing of cartridges which require loaded primers might become as dangerous as firing loaded cartridges. By forming a clearance-space in the inner end of the anvil and by contracting the open inner end of the primer-body the fire produced by the explosion of the fulminate is allowed to speedily unite in the clearance-space, after which it is drawn together, as it were, by the retaining-neck into one tongue of flame, passing thence into the powder.

A comparison of Figs. 1 and 2 shows a shortening of the primer-body or shell by contracting its open end to form a condensed and thickened neck, as described.

My improved primer may be used either in shot-shells, whether made of metal or paper, or in cartridges furnished with bullets.

In Fig. 5 of the drawings I have shown one of my improved primers applied to a paper-shell cartridge D, having a sheet-metal head D' and a reinforce D², which is by preference formed of a long tightly-wound coil of paper and located within the metal head D'. The said head in the cartridge shown has no primer-pocket, but a perforation d through which the body of the primer passes, and thence directly through the reinforce D² into the powder E in front of the same. The edge of the opening d is set inward to form an annular seat d', affording a bearing for the flange A' of the primer-body.

My improved primer is well adapted for use in paper shot-shells, but, as before mentioned, has a much wider range of application.

I would therefore have it understood that I do not limit myself to the exact construction shown and described, but hold my right to make such changes and improvements as fairly fall within the spirit and scope of my invention.

Having fully described my invention, I claim as new, and desire to secure a Patent, is—

The herein-described primer for shells, consisting of a sheet-metal body and a flat sheet-metal anvil, the primer-body having its open inner end contracted to form a cylindrical, long and projecting, thickened and constricted neck, the neck being therefore reinforced retaining-neck being in diameter than the remaining part of the said primer-body, and the said neck being straight corresponding bearing, the pointed outer end forming a high surface, and an indented inner end forming a clearance-space, the pointed outer end of the anvil resting upon the fulminate located in the closed outer end of the primer-body, the retaining-neck of the primer-body being smaller in diameter than the width of the anvil which it holds firmly in place, the primer-body against the force of the fulminate when exploded, and the clearance-space of the anvil and the neck of the primer-body to permit the quick union of the fulminate and the drawing of the same together into a single flame which ward through the neck to the outside substantially as set forth.

In testimony whereof I have signed the specification in the presence of the following witnesses.

JOHN G.
